UNITED STATES PATENT OFFICE.

CHARLES E. INGLIS, OF MALDEN, MASSACHUSETTS.

NON-REFILLABLE BOTTLE.

1,111,155.

Specification of Letters Patent.

Patented Sept. 22, 1914.

Application filed January 2, 1913. Serial No. 739,711.

To all whom it may concern:

Be it known that I, CHARLES E. INGLIS, a subject of the King of Great Britain, and resident of Malden, in the county of Middlesex and State of Massachusetts, have invented certain new and useful Improvements in Non-Refillable Bottles, of which the following is a specification.

This invention has for its object to provide a simple, efficient and relatively inexpensive device whereby the practical refilling of a bottle is prevented.

The invention consists in the improvements which I will now proceed to describe and claim.

Of the accompanying drawings, forming a part of this specification:—Figure 1 represents a longitudinal section of a portion of the neck of a non-refillable bottle embodying some of the features of my invention, the neck being in an upright position; Fig. 2 represents a view similar to Fig. 1, showing the neck inverted and in position for pouring; Fig. 3 represents a section on line 3—3 of Fig. 1; Fig. 4 represents the several movable members of the device in side elevation, said members being separated from each other; Fig. 5 is a detail plan view of the cup-shaped weight, detached; Fig. 6 is a view similar to Fig. 1, but illustrating a different embodiment of my invention.

The same reference characters indicate the same parts in all of the figures.

Referring first to Figs. 1 to 5 inclusive, 12 represents a bottle neck, and 13 a ring of glass, or other suitable material, secured within the neck at a suitable distance below the mouth thereof. Said ring has an upwardly tapering tubular extension 14, the edge of which is internally beveled to form a valve seat 15. The inner surface of the tubular extension 14 forms the outlet of the bottle. 16 represents a valve which is preferably cup-shaped, or concavo-convex, its lower external surface being formed to fit accurately the valve seat 15 and prevent access of liquid to the bottle when the valve is seated. 17 represents a guard, which is preferably a disk firmly secured to the interior of the bottle neck, above the valve seat, and spaced therefrom sufficiently to permit the opening of the valve, as indicated by Fig. 2. The marginal portion of the guard 17 is provided with notches 18, forming liquid passages. The valve 16 has a stem 19 extending below the plane of the ring 13 when the

bottle is in normal upright position, said stem having loosely connected thereto an inverted cup-shaped weight 20. The stem 19 passes through a central hole of the weight, the fit being such as to permit of sliding movement longitudinally of the stem with little or no swinging or rocking movement. The extent of relative movement of the valve and weight is limited by suitable means, such as a glass stop ring or washer 22 cemented or fused to the stem, and bearing loosely on the weight. The inverted cup or weight 20 is formed with holes 23, 24 for the passage of liquid when the bottle is inverted as shown in Fig. 2.

When the bottle is in normal or upright position as shown in Fig. 1, liquid cannot be poured thereinto, because the valve 16, due not only to its own weight and that of the weight 20 but also to the weight of liquid which would fill the cup 16, is seated so firmly upon the valve seat 15 as to prevent any liability of liquid entering the bottle. The loose connection between the two cup-shaped members permits the member 20 to occupy such position as to readily permit the escape of liquid the moment that the bottle is tilted enough to begin pouring therefrom. When the bottle is nearly emptied and is inverted to substantially such position as shown in Fig. 2, the cup-shaped member 20 will bear against the ring 13, but owing to the perforations in said member 20 liquid can escape so as to pass around the stem 19 of the cup-shaped member 16. Fraudulent filling of the bottle, by exhausting the air therefrom when the bottle is in upright position and liquid is placed in the bottle neck above the valve, is prevented because the liquid that would be poured into the neck for such purpose would fill the cup-shaped recess in the top of the valve member 16 and so add to the weight thereof that an attempt to exhaust air from the bottle would not lift the valve sufficiently to permit any appreciable amount of liquid to pass into the bottle. If the bottle is held in an approximately vertical inverted position when air is exhausted therefrom, the liquid caused by the vacuum to flow upwardly toward the interior of the bottle will entrap air in the cavity of the now inverted valve 16, and will float the valve to its seat without moving the weight 20, the freedom of the stem 19 to slide in the central orifice in the weight enabling the entering liquid to float and close

the valve without overcoming the inertia of the weight, which under the described conditions remains in the position shown by Fig. 2. It will be seen therefore that although the weight is effective in holding the valve on its seat when the bottle is upright it does not act when the bottle is inverted, the valve being closable by a vacuum induced flow of liquid as easily as it would be if the weight were not present.

Referring now to Fig. 6, which illustrates another embodiment of the invention, the ring which supports the valve seat is shown at 131, said ring having a thin flange 141, the inner edge of which forms a valve seat 151 for the valve 16. The flange 141 is so thin that any such unusual external pressure as is sometimes employed to refill bottles of other types would cause the cup-shaped valve 16 to bear so strongly against the valve seat as to break the said seat so that the valve 16 and its loosely connected weight 20 will immediately pass to the bottom of the bottle, so that the mere fact of the presence of these parts in the bottom of the bottle would indicate that the bottle did not still retain its original contents. The ring 131 is of course made so thin that its internal diameter will be of a size to permit the cup-shaped valve 16 to pass through the ring when the flange 141 is broken.

The valve 16 and its stem 19 are formed with a small aperture or vent 26, the upper end of said vent aperture when the bottle is upright being closed by a vent cover 27 having a small guiding stem 28 extending down through the vent 26, said stem 28 being small enough so that it does not completely fill the vent aperture, and being also long enough so that said guide stem will not slide entirely out of the vent aperture when the bottle is inverted. The object of the vent 26 and its cover 27 is to prevent fraudulent filling of the bottle by exhausting air therefrom when the bottle is in an upright position, liquid being placed in the bottle neck above the valve. If the vent 26 and its cover 27 were not provided, the operation of exhausting air from the bottle neck above the valve, and through a cap temporarily applied to the neck, may under certain conditions tend to open the valve and permit a relatively rapid flow of liquid contained in the upper por-

tion of the neck into the bottle. The vent 26 and its cover 27 being provided, the withdrawal of air from the bottle neck will cause the escape of a limited quantity of air from the interior of the bottle through the vent, so that the valve itself will not be opened. The vent is of such small capacity that only an inconsiderable quantity of liquid can pass through it into the bottle. Moreover, the cover 27, which is of considerably larger area than the vent, has a constant tendency to close the vent, so that while the vent serves the purpose of preventing the opening of the valve in the described operation, it does not practically permit the fraudulent refilling of the bottle.

All of the parts described may be made of glass, although I do not limit myself to constructing them of such material.

Having described my invention, I claim:

1. A non-refillable bottle comprising a ring secured in the neck of the bottle and forming a valve seat, a cup-shaped valve having its open end extending toward the mouth of the bottle, the closed end of said valve being formed to close the valve seat and having an inwardly projecting stem 80 provided with a stop, and a weight below the valve seat provided with a central orifice in which the said stem has a limited sliding movement, the valve being adapted to be floated to its seat without corresponding movement of the weight.

2. A non-refillable bottle comprising a ring secured in the neck of the bottle and provided with an opening forming a valve seat, a cup-shaped valve having a vent aperture in its bottom, and a vent cover located in said cup-shaped valve.

3. A non-refillable bottle comprising a ring secured in the neck of the bottle and provided with an opening forming a valve seat, a cup-shaped valve having a vent aperture in its bottom, and a vent cover located in said cup-shaped valve, said vent cover having a guiding stem in the vent aperture.

In testimony whereof I have affixed my signature, in presence of two witnesses.

CHARLES E. INGLIS.
